UNITED STATES PATENT OFFICE.

HARRIET B. CALVERT, OF RIVERSIDE, CALIFORNIA.

IRON REST.

Application filed October 26, 1925. Serial No. 64,899.

This invention relates to an improved attachment for common sad irons, electric irons, and the like, wherein the same is constructed to provide a permanently attached rest so that the iron may be turned up to the vertical position, and effectively supported in that position to prevent scorching and burning of the article being pressed.

My principal aim is to generally improve upon attachments of this class by providing one of comparative simplicity and durability which is formed from a single plate of metal fastened upon the rear end and back of the iron to provide an efficient support or rest for the iron while in its inoperative vertical position.

Other features and advantages of the invention will become apparent from the following description and drawing.

20 In the accompanying drawing forming a part of this application and in which like numerals are employed to designate like parts throughout the same:

Figure 1 is a side elevation of the iron 25 in its vertical position showing the improved attachment in place and in use.

Figure 2 is a perspective view of the attachment disconnected from the iron.

Referring to the drawing in detail, the 30 reference character 1 designates the handle of a common ordinary electric iron, 2 represents the body of the iron, 3 an electric socket, and 4 an electric cord connected thereto. It is immaterial whether the iron 35 be an electric iron, or the old fashioned sad iron.

The attachment is represented generally by the reference character 5. As before stated, it is formed from a single plate of metal, 40 preferably of polished steel or similar sturdy material. The plate is bent to provide a base 6, 7 designates a vertically up-turned front flange, and 8 designates apertured attaching ears which are turned inwardly to 45 dispose them in spaced parallelism with the base portion. Extending up in parallelism with the front flange 7 are the attaching arms 9 which are apertured at their free

ends to permit passage of appropriate fastenings therethrough for fastening them to 50 the back or top or body of the iron.

In practice, the ears 8 are fastened to the rear end of the iron as shown in Figure 1 at a point near the bottom, but spaced above it so that the attachment will not interfere 55 with the work. This disposes the base in spaced parallelism to the rear end of the iron, and the base is preferably of a proportion to extend beyond the back or top of the iron. This positions the attaching arms 60 for connection to said back. By referring to Figure 1, a good idea of the method of attaching the attachment may be obtained. The attachment is at all times in place and is ready for use whenever necessary. While 65 ironing, the iron can be turned up on end to the vertical position shown and supported upon the base without permitting burning or scorching the apparel being pressed.

No doubt, by carefully considering the 70 description in connection with the drawing, persons familiar with structures of this kind will be able to obtain a clear understanding of the same. Therefore, a more lengthy description is thought unnecessary. 75

While the preferred embodiment of the invention has been shown and described it is to be understood that minor changes coming within the field of invention claimed may be resorted to if desired. 80

Having thus described the invention, what I claim as new and desire to secure by Letters Patent is:—

A supporting attachment for an iron comprising a single plate of metal bent to provide a base, a right angular front flange, apertured attaching ears on said flange, and a pair of attaching arms bent at right angles to the base, the ears being adapted to be connected with one end of the iron and the 90 arms being adapted to be connected with the top thereof, to dispose the base in spaced parallelism to said end of the iron.

In testimony whereof I affix my signature.

HARRIET B. CALVERT.
